UNITED STATES PATENT OFFICE.

RICHARD F. HOYT, OF OLNEY, PHILADELPHIA, PENNSYLVANIA, ASSIGNOR, BY MESNE ASSIGNMENTS, TO UNDERWOOD COMPUTING MACHINE COMPANY, OF NEW YORK, N. Y., A CORPORATION OF NEW YORK.

TYPE-WRITING MACHINE.

1,250,883.

Specification of Letters Patent. Patented Dec. 18, 1917.

Application filed November 1, 1913. Serial No. 798,638.

To all whom it may concern:

Be it known that I, RICHARD F. HOYT, a citizen of the United States, residing in Olney, Philadelphia, in the county of Philadelphia and State of Pennsylvania, have invented certain new and useful Improvements in Type-Writing Machines, of which the following is a specification.

My invention relates to means for conveniently severing a web or work-sheet after it has been written upon in a typewriting machine.

An object of the invention is to provide a simple severing blade structure which may be quickly attached to or removed from the machine, and adapted for use with standard machines with only slight alterations in the latter.

The device is shown on an Underwood typewriting machine, and may comprise a tearing blade located above the platen and adjustably supported on the usual brackets which carry the paper guide fingers at the front of the platen. The blade may have a sliding connection at one end with one bracket, permitting either paper guide to be adjusted longitudinally of the platen, and at its other end the blade may be suitably clamped, as by means of a thumb screw to the other bracket, permitting the blade to be secured in position or released for removal from the machine by simply operating the thumb screw.

Other features and advantages will hereinafter appear.

In the accompanying drawings,

Figure 1 is a perspective view of the invention.

Fig. 2 is a fragmentary view showing the left-hand end of the blade and the corresponding bracket for the paper guide finger, the parts being shown disassembled.

Fig. 3 is a similar view of the right-hand end of the blade and right-hand bracket.

Fig. 4 is a fragmentary sectional elevation view of the blade and supporting means.

Fig. 5 is a front elevation view showing the blade in full lines and the associated parts in broken lines.

The usual rotary platen 1 may be journaled in a platen frame comprising ends 2 and 3 in which is also mounted a rod 4 extending longitudinally over the platen. On said rod are mounted the right-hand and

left-hand bracket arms 5 and 6, respectively, to which are connected, as by means of screws 7, paper guide fingers 8 extending downwardly and forwardly over the front face of the platen to guide the work-sheets or webs *a* over the printing zone and from thence toward the rear of the machine. The guide fingers 8 carry the usual feed rolls 9.

The paper-severing means may be of suitable character and are here shown as consisting of a blade or cutter 10 located over the platen and extending longitudinally thereof, the edge 11 of said blade in the present example consisting of serrations or teeth. One end of the cutter 10, as shown, the left-hand end, is bifurcated to form guide arms 12 which straddle the bracket 6, said arms being supported and guided in recesses or notches 13 formed in the bracket, whereby the blade and said bracket are relatively adjustable longitudinally of the platen, and the blade held against movement in other directions relative to its supporting bracket. The right-hand end of the blade 10 may be formed with a head or thickened portion 14 having a screw-threaded opening 15 to receive a thumb screw 16 which extends through an opening 17 in the bracket 5, whereby the right-hand end of the cutter 10 may be clamped to said bracket, the head 14 also forming an offset to provide space between the blade and bracket 5 for the upper end of the guide 8 and the nut or washer 7 into which the ends of the screws 7 are threaded. When thus clamped, the paper knife is securely held in position, and at the same time permits either one or both of the paper guide fingers 8 to be adjusted longitudinally of the platen to accommodate webs or work-sheets of different widths. That is, the left-hand bracket 6 and the guide finger 8 thereon are adjustable along the platen owing to the sliding connection with the arms 12, such sliding connection also permitting the right-hand bracket 5 with its guide finger 8 to be adjusted along the platen while the bracket 6 remains stationary, the connection 12, 13 permitting the knife 10 to move with the bracket 5.

By unscrewing the thumb nut 16 to release it from the knife, the latter may be removed by lifting the right-hand end free of the bracket 5 and then moving the knife to the right to disconnect it from

the bracket 6. The slight tilting movement of the blade in thus removing it is permitted either by a slight amount of play between the arms 12 and the bases of the 5 notches 13, or by the resiliency of the arms 12. This slight play or loose connection between the bracket 6 and the blade, also serves to permit a limited movement of each guide finger 8 and its feed roll 9, 10 toward and from the platen independently of the other guide finger, whereby each guide finger and roll maintain their operative position and normal pressure against the work, regardless of variations in the 15 thickness of the work-pieces, or irregularities in the platen.

It will be seen that the blade may be quickly attached to or removed from the machine, requiring only the manipulation of 20 the single thumb screw or holding device, and when in position does not interfere with the adjustment of the paper guide fingers. The upper portion of the blade is preferably inclined rearwardly in the general direction 25 of the leading end of the web or work-sheet *a*, so that the latter is bent but little out of its course when brought to the severing edge, and the blade is presented at a suitable angle to the paper when a section is 30 being torn off.

The guide fingers 8, with their brackets, are preferably movable in the usual way about the rod 4 to permit said fingers to be lifted from the platen.

35 Variations may be resorted to within the scope of the invention, and portions of the improvements may be used without others.

Having thus described my invention, I claim:

40 1. In a typewriting machine, the combination with a platen and paper guides associated therewith, said guides adjustable relatively thereto and relatively to each other, of a paper-severing device secured to one of 45 said guides and loosely supported and guided by the other guide, whereby both guides are normally movable for adjustment relatively to the platen and relatively to each other.

50 2. In a typewriting machine having a revoluble platen, the combination with a paper-severing blade movable longitudinally within the limits of the platen length, of paper guides, and individually movable brackets 35 carrying said guides and having respectively

a fixed and a sliding connection with opposite ends of said blade, whereby said blade and guides are adjustable longitudinally of said platen, each guide being free for such adjustment independently of the other, said 60 sliding connection formed to permit the blade to be separated from the guide by a relative movement of the guide and blade lengthwise of the platen.

3. In a typewriting machine having a revoluble platen, the combination with a paper-severing blade shorter than the platen and movable longitudinally within the limits of the platen length, of paper guides, brackets adjustable longitudinally of the 70 platen and carrying said guides, and a clamp connecting one bracket to one end of said blade, the other end of the blade slidably mounted on the other bracket whereby said blade and guides are adjustable longitudinally of said platen, one of said brackets, with a guide and blade carried thereby, being adjustable relatively to the other bracket and guide, to vary the width of the space 75 between said guides, said clamp releasable 80 to disconnect one end of the blade, the other end being then free to slide out of engagement with its bracket for removing the blade from the machine.

4. In a typewriting machine, the combination with a roller platen, of paper guides mounted to swing toward and from the platen into and out of position to hold the work-pieces against the platen, said guides independently adjustable lengthwise of the 90 platen, a paper-severing blade, and a clamp to releasably connect one end of the blade with one paper guide, the other end of the blade being provided with an open-ended slot whereby the blade has a sliding connection 95 with the other paper guide, permitting relative adjustment of the latter and the blade lengthwise of the platen, and holding the blade against displacement in a direction transversely to the platen, said connection 100 also permitting the blade to be removed from the machine by releasing said clamp and sliding the blade lengthwise of the platen to free the slotted end of the blade from the paper guide.
